UNITED STATES PATENT OFFICE.

ROBERT BRINCKMANN, OF MICHIGAN CITY, INDIANA.

DESIGN FOR A DISPLAY-CASE.

SPECIFICATION forming part of Design No. 23,685, dated October 9, 1894.

Application filed April 23, 1894. Serial No. 508,741. Term of patent 7 years.

To all whom it may concern:

Be it known that I, ROBERT BRINCKMANN, a citizen of the United States, residing in Michigan City, in the county of La Porte, in the State of Indiana, have invented a new and original Design for Display-Cases, of which the following is a specification, reference being had to the accompanying drawing, forming a part of this specification.

10 The drawing shows in perspective view a display case embodying my design.

15 My design comprises a series of rectangular figures and curves harmoniously composed and combined as shown in the drawing.

20 As illustrated in the drawing the design comprises a series of rectangles B B arranged in horizontal rows and vertical tiers. Each of these main or central rectangles B has at its upper and lower sides two horizontally disposed smaller rectangles b b, and at its two ends two vertically disposed rectangles b' b'. Around each rectangle B there are thus four marginal rectangles b b and b' b', the five rectangles B, b, b, b', b' constituting one group.

25 The series of vertically disposed rectangles b' b' taken together constitute a series of columns in the main central portion of the design. All the rectangles B, b and b' are contained within the main rectangle A, constituting the main central outline of the design.

30 Within the main rectangle A and surrounding each group of marginal rectangles b, b, and b', b' are narrow horizontal divisional spaces a a, and narrow vertical divisional

35 spaces a' a'.

C is the base, composed of a series of par-

allel lines c, c', c², c³, c⁴, c⁵, the parallel lines c and c' being joined at their ends by vertical lines c⁶ c⁶, the parallel lines c' and c² being joined by inwardly curved lines c⁷ and the 40 parallel lines c² c³ being joined by vertical line c⁸ and the parallel lines c³ c⁴ and c⁴ c⁵ being joined by outwardly curved lines c⁸ c⁸ and c⁹ c⁹, thus giving the base C a molded appearance.

45

D is the top, comprising a narrow, horizontal, rectangular figure having ogee curved ends d d.

D' D' are wings constituting extensions of the top, and having ogee curved outer ends 50 d' d', and concave curved inner ends d² d² of the top D.

F F are brackets, having an inward curve f at their upper edge, a double curved inclined edge f' and two curves f² f³ at the vertical side where they meet the main rectangular outline A. Below the brackets F F, one on each side of the main central rectangle A, are two brackets G G, one on each side, composed each of a lower double curve g, an upper 55 double curve g' and an outwardly inclined straight line g², which is ornamented by three narrow rectangular figures g³, g⁴, g⁵, disposed as shown.

60

I claim—
The design for a display case herein shown and described.

ROBERT BRINCKMANN.
